UNITED STATES PATENT OFFICE.

CHAUNCEY M. PARK, OF FLINT, MICHIGAN.

CARBURETOR.

Application filed February 11, 1919. Serial No. 276,273.

To all whom it may concern:

Be it known that I, CHAUNCEY M. PARK, a citizen of the United States of America, residing at Flint, in the county of Genesee, 5 and State of Michigan, have invented new and useful Improvements in Carburetors, of which the following is a specification.

The object of the invention is to provide a new and novel form of carburetor for use 10 in conjunction with internal combustion engines, the carburetor working on the principle of a deposit of a film of gasoline on a perforated surface. The suction stroke of 15 the engine with which the carburetor is used serves to draw in a quantity of air through this perforated surface which blows the film of gasoline into a fine spray and to this spray air is added to form a properly explosive mixture, said air being admitted 20 through a separate valve controlled inlet.

The invention is illustrated and described in a specific embodiment, to which, however, it is not to be restricted. The right is reserved to make such changes or alterations 25 as the actual reduction to practice may suggest, in so far as such changes or alterations are compatible in spirit with the annexed claim.

The same numerals of reference designate 30 the same parts throughout the several figures of drawings, wherein:

Figure 1 is a central longitudinal sectional view through the improved carburetor.

Figure 2 is a section on the line 2—2 of 35 Figure 1.

Figure 3 is a section on the line 3—3 of Figure 1.

As shown, the invention comprises a cylindrical fuel chamber 1, which is of annular 40 shape and surrounds a tubular member 2, which depends below the bottom of the chamber 1 and extends above the top thereof, the upper end of the tubular member 2 being formed with a flange 3 by means of 45 which it may be bolted to the intake manifold of an internal combustion engine.

Substantially at an intermediate point in the height of the chamber 1 there is a hollow member 4 having the shape of a cross. This hollow member 4 is disposed within the tubular member 2 so that the arms of which it is composed are radially positioned within the said tubular member. This hollow member 4 on the upper faces of its arms is provided with a plurality of perforations 5 and perforations 6 exist in the wall of the

tubular member directly above the upper faces of the arms of hollow member 4, and these perforations 6 establish communication between the interior of the fuel chamber 1 and the interior of the tubular member 2.

Communication is further established between the tubular member 2 and the chamber 1 by means of a plurality of perforations 7 formed in the wall of the tubular member 65 just below the top of the chamber 1. The chamber 1 is air tight except for what air might be admitted thereinto through the perforations 6 and 7, the latter perforations admitting the necessary air on top of the 70 fuel to permit it to leave the chamber 1 through the perforations 6.

The design of the invention requires the admission of air to the hollow member 4 and to this end there is a right angular shaped 75 tubular member 8, which communicates with one arm of the hollow member 4 through the wall of the tubular member 2 at the point where that arm connects with the wall of the tubular member. The tubular member 80 8 terminates at the outer wall of the fuel chamber 1 adjacent the top of the latter and is formed with an appropriate seat with which a conical shaped valve 9 may engage, this valve being formed with a threaded 85 stem 10 and a head 11 to permit the stems being turned and the valve operated by hand, the stem being supported and the valve thus positioned by an appropriate bracket 12 carried by the fuel chamber on the outer 90 wall thereof. It is obvious that the amount of air admitted to the hollow member 4 may be regulated by the proper adjustment of the valve 9.

The hollow member 4 is provided with upstanding side walls 13 standing above the upper faces of the arms, these walls being for a purpose later made apparent.

A butterfly valve 14 is carried in the tubular member 2 below the plane of the bottom 95 of the fuel chamber 1 to regulate the amount of air admitted into the tubular member 2 from the lower end thereof, which opens into the atmosphere. The fuel chamber adjacent the top and at a point substantially diametrically opposite the valve 9 is formed with a nipple portion 15 into which there is screwed a valve element 16, the latter having connected therewith a tube or pipe 17, which is lead to the fuel tank positioned at any appropriate point for use in conjunction with 100 the engine to which the carburetor is at-

tached. The valve element 16 is formed with an appropriate seat for engagement by the conical shaped needle valve 18, the latter being carried by a float 19, which is 5 swingingly secured to the interior wall of the chamber 1 adjacent the nipple 15, as indicated at 20. This float 19 is made preferably of cork and is of annular shape, standing in surrounding relation to the tubular member 10 2. Obviously, when the fuel in the tank 1 reaches the proper height, the float 19 will rise and seat the valve 18, thus cutting off the supply of fuel to the chamber 1.

With the present invention the proper 15 height of the fuel in chamber 1 and the height to which the float 19 closes the valve 18, is that height which brings the level of the fuel in the plane of the perforation 6. A certain amount of fuel thus passes through 20 the perforations 6 and settles on the upper faces of the arms of the hollow member 4, this fuel settling in the form of a film. When the engine with which the carburetor is used is effecting its suction stroke, the suc- 25 tion created in the intake manifold obtains in that part of the tubular member 2 above the hollow member 4 (this portion of the tubular member being a mixing chamber) and air is drawn through the tubular mem- 30 ber 8 and into the hollow member 4, passing through the minute perforations 5 and throwing off the film of fuel in the form of a spray. At the same time air is drawn in through the lower part of the tubular mem- 35 ber 2—that is, as much air as the position of the butterfly valve 14 will permit—and

the air thus admitted through the bottom part of the tubular member passes through the spaces left between the arms of the hollow member 4 and this air affects the proper 40 constituency of fuel mixture from the spray.

The upstanding walls 13 serve as retaining means keeping the film of fuel on top of the upper faces on the arms of the hollow member 4 and these arms define the openings 45 or spaces through which air is admitted from the bottom part of the tubular member 2 to the upper part thereof, which constitutes the mixing chamber.

The provision of the perforation 7 makes 50 for the equalization of the pressure within the fuel chamber 1 and the mixing chamber.

The invention having been described, what is claimed as new and useful is:

In a carburetor, a fuel chamber, a tubular member which the fuel chamber surrounds, the tubular member having means for connection to the intake manifold of an engine, a hollow member disposed within the tubular member and having a perforated upper 60 face, the tubular member being perforated adjacent the upper face of the hollow member to effect communication with the fuel chamber, whereby fuel in the fuel chamber may be admitted on top of the hollow mem- 65 ber to form a film thereon, and means for admitting air to the said hollow member for the useful purpose specified.

In testimony whereof I affix my signature.

CHAUNCEY M. PARK.
